(57) **CLAIM**

I claim, the ornamental motorcycle ignition, as shown and described herein.

DESCRIPTION

FIG. 1 is a perspective view of a motorcycle ignition in accordance with my invention;

FIG. 2 is a top, plan view of the motorcycle ignition shown in FIG. 1;

FIG. 3 is a plan view of a base plate of the motorcycle ignition shown in FIG. 1;

FIG. 4 is an elevation view of the motorcycle ignition shown in FIG. 1, with FIG. 4 being shown from a first side;

FIG. 5 is an elevation view of the motorcycle ignition shown in FIG. 1, with the view being shown from a second side rotated 90° from the view shown in FIG. 4;

FIG. 6 is an elevation view of the motorcycle ignition shown in FIG. 1, with the view being shown from a third side rotated 180° from the view shown in FIG. 4; and,

FIG. 7 is an elevation view of the motorcycle ignition shown in FIG. 1, with the view being shown from a fourth side rotated 270° from the view shown in FIG. 4.

The broken lines shown illustrate portions of the motorcycle ignition that form no part of the claimed design.

1 Claim, 5 Drawing Sheets
